UNITED STATES PATENT OFFICE.

HARRY C. KNEEZEL, OF NEW YORK, N. Y.

DESIGN FOR A BADGE.

• 60,150.

Specification for Design.

Patented Jan. 3, 1922.

Application filed January 18, 1919. Serial No. 271,928. Term of patent 3½ years.

To all whom it may concern:

Be it known that I, HARRY C. KNEEZEL, a citizen of the United States, residing at New York City, county of New York, State of New York, have invented a new, original, and ornamental Design for a Badge, of which the following is a specification.

This invention relates to a new, original and ornamental design for a badge shown in the accompanying drawing forming a part of this specification in which the figure shows a front view of the badge.

I claim:

The ornamental design for a badge as shown.

HARRY C. KNEEZEL.
